UNITED STATES PATENT OFFICE.

JAMES SCARR, OF RANDSBURG, CALIFORNIA.

COLLAPSIBLE CRATE.

1,227,079.

Specification of Letters Patent. Patented May 22, 1917.

Application filed November 23, 1915. Serial No. 63,059.

To all whom it may concern:

Be it known that I, JAMES SCARR, a subject of the King of Great Britain, residing at Randsburg, in the county of Kern and State of California, have invented certain new and useful Improvements in Collapsible Crates, of which the following is a specification.

This invention relates to collapsible crates or coops, and has for one of its objects to improve the construction and increase the efficiency and utility of devices of this character.

With these and other objects in view the invention consists in certain novel features of construction as hereafter shown and described and then specifically pointed out in the claims; and in the drawings illustrative of the preferred embodiment of the invention—

Figure 1 is a perspective view from the top, front, and one end, with the device in open or operative position;

Fig. 2 is a perspective view showing the parts in collapsed or closed position;

Fig. 3 is a detached perspective view of the blank from which one of the combined corner and stop members is constructed;

Fig. 4 is a detached perspective view of the combined corner and stop member bent into operative position;

Fig. 5 is an enlarged perspective view, detached, of one of the catch devices;

Fig. 6 is a longitudinal sectional elevation of the device on the line 5—5 of Fig. 1;

Fig. 7 is a transverse sectional elevation;

Fig. 8 is a rear elevation;

Fig. 9 is a detached perspective view of one of the elongated hinge members whereby the top is hingedly united to the back;

Fig. 10 is a sectional detail illustrating the arrangement of the parts when folded.

Corresponding and like parts are referred to in the following description and indicated in all the views of the drawings by the same reference characters.

The improved device may be constructed of any required size and is more specifically adapted for shipping poultry and the like, but may be employed for shipping other products or commodities, and it is not desired, therefore, to limit the device to any specific purpose, but for the purpose of illustration is shown arranged as a poultry shipping crate or coop, and comprises a bottom

member represented as a whole at 10. Disposed upon the bottom 10 at its side edges is a rear stop member 11 and a forward stop member 12, the members 11—12 being nailed or otherwise secured to the bottom 10, and the connection between the members 10—11—12 further strengthened by terminal straps 13 of sheet metal. Hingedly united at 14 to the member 12 is a front vertical member comprising a lower rail 15, an upper rail 16, end members 17—18, a central longitudinal member 19, and a plurality of vertical slats 20. The members 15—16 and 17 are strengthened at their confronting ends by metal straps 21 of sheet metal. The members 15—16—17—18 and 19 are preferably of wood, while the slats 20 and the straps 21 are of metal.

Hingedly united at 22 to the rear vertical member 11 is a back member comprising a lower rail 23, an upper rail 24, end members 25—26, a central longitudinal member 27 and a plurality of vertical slats 28. The members 23—24—25 and 26 are strengthened at their confronting ends by metal straps 29. The members 23—24—25 and 26 are preferably of wood, while the slats 28 and the straps 29 are of metal.

The front and rear members are substantially alike and are foldable inwardly into parallel relation with the bottom 10 and in alignment transversely of the coop or crate, as indicated in Fig. 2.

The end members each comprise a lower rail 30, an upper rail 31, end rails or stiles 32, an intermediate longitudinal stay member 33, and a plurality of vertical slats 34, the end structures being thus similar to the front and back portions. The end members are hingedly united at 35 to the bottom 10 and fold inwardly into parallel relation to the bottom and in close proximity thereto. The members 11—12 are of sufficient height so that when the ends front and back are folded inwardly a considerable space is left between confronting faces of the members.

Connected to the upper rail members 16 and 24 are resilient stop devices 36 having terminal offsets 37 to project into the paths of the end members and hold them in their vertical position, while at the same time the end members are releasable by manually displacing the stop members. The inner faces of the terminals 37 are inclined at one side, so that the members 36 will be displaced au-

tomatically when the end members are moved into upper position, as will be obvious.

The top portion of the improved device 5 comprises a forward longitudinal rail 38, a rear longitudinal rail 39, end rails 40-41, an intermediate longitudinal rail 42, and a plurality of transverse intermediate rails 43. The rails 43 are preferably spaced apart a 10 less distance than the distance between the transverse intermediate rails and end rails, as illustrated in Fig. 1, space between the members 43 constituting the door-way openings through which the fowls are inserted 15 and removed. A plurality of slats 44 are located between the rails 38-39 and between the rails 43 and the end members, as shown in Fig. 1.

Guide rods 45 extend through the members 38-39 and 42 and relatively near the rail members 43, and mounted to slide upon the guide members are plates 46-47, the plate 46 being arranged to slide upon the guides 45 between the rails 39 and 42, while 25 the plate 47 is arranged to slide upon the guide rods between the rails 38-42. Connected at their outer ends to the plate 46 are a plurality of slats 48, while a similar plurality of slats 50 are connected at their outer 30 ends to the plate 47. The slats 48 extend through the intermediate member 42 from one side and are provided with eyes 51 which engage around the slats 50, the slats 50 extending through the intermediate member 42 from the other side and are provided with eyes 52 which engage around the slats 48. By this means when the plate 46 is moved inwardly toward the intermediate rail 42 the eyes 51 will slide over the slats 40 50 which thus serve as guides therefor, and when the plate 47 is moved toward the longitudinal member 42 the eyes 52 will slide over the slats 48 and be guided thereby. A spring catch 53 is connected to the rail 38 45 and yieldably engages the plate 47, while a similar yieldable catch 54 is connected to the rail 39 and yieldably engages the plate 46. By this means the plates 46-47 and their attachments are yieldably maintained in 50 their outer position, but can be released and moved inwardly when required. By this simple arrangement it will be obvious that movable doors or closures are provided for the space between the members 43 to enable 55 the fowls to be inserted or removed. It will also be noted that two independent closures are provided, one at each side of the intermediate member 43, so that fowls may be inserted or removed at either side of the crate 60 or coop.

Attached to the lower and upper rail members 23-24 are strap-like hinge members 55, the body of the strap devices being spaced away from the adjacent faces of the 65 members 23-24 and 27 and operating as

guide devices, as well as hinge members, as hereafter explained. Pivoted at 56 to the member 39 of the top are hinge members to each of which a link 57 is swingingly coupled and adapted to engage beneath the combined hinge and guide members 55. The parts 55 and 57 are so proportioned that when the top portion of the device is in closed position, as shown in Fig. 7, the links 57 will be located at the upper end of the members 55, and when the device is collapsed or folded, as shown in Fig. 2, the links 57 will be located at the lower end of the members 55, as illustrated in Fig. 10.

Guard members 58 are attached to the members 23-24 of the back and located relatively close to the members 55 and project beyond their outer faces, and thus serve to protect the members 55 from contact with surrounding objects.

Connected to the front vertical member 12 of the bottom and to the top member 16 of the front are plates 59, the plates being located a short distance from each end of the device and preferably in alinement with the 90 hinges 14 and 22. Each plate is provided with a perforated lateral offset 60 and a swinging catch 61, the terminal of the catch being widened, as shown at 62 and perforated, the perforations registering with the 95 perforations of the offset 60 to receive a fastening device, such as a padlock or the like when the member 61 is located in one position.

Connected to the member 38 of the top are 100 hinge members 63 in each of which a loop or link 64 is mounted to swing and adapted to engage beneath the latch devices 61 which are associated with the member 16 when the crate or coop is in open position, as shown in Fig. 1, and to engage with the latch devices 61 which are associated with the member 12 when the crate or coop is collapsed, as shown in Fig. 2. The links or loops 64 may be released by turning the members 61 into their 105 upper position, as will be obvious.

The straps 29 which are attached to the upper corners of the front and back members are first formed as shown in Fig. 3 with a longitudinal cleft and then bent into 115 the shape shown in Fig. 4, whereby a stop lug 65 is produced to extend into the paths of the end members as shown in Fig. 1 to limit the outward movement of the latter.

The stops 65 and the portions 37 of the 120 spring catches 36 thus coact to hold the end members in open position.

Having thus described the invention, what is claimed as new is:—

1. A folding receptacle including 125 foldable front rear and end members and a movable top, guide devices swingingly connected at one end to the rear member, and loops carried by the top and slidably engaging the guide devices at their other ends, 130

said guide devices and loops coöperating to form a flexible hinge connection between the top and back member when the receptacle is in open position and to hold the rear 5 of the bottom in position when the receptacle is collapsed.

2. A folding receptacle including inter-foldable front rear and end members and a movable top, guide devices connected at their 10 ends to the rear member and spaced intermediate their ends therefrom, and loops swingingly connected at one end to the top and slidably engaging the guide devices, at their other ends, said guide devices and 15 loops coöperating to form a flexible hinge connection between the top and back member when the receptacle is in open position and to hold the rear of the bottom in position when the receptacle is collapsed.

3. A folding receptacle including inter-foldable front rear and end members and a movable top, guide devices swingingly connected at one end to the rear member, loops carried by the top at its rear and slidably 25 engaging the guide devices at their other ends, holding devices, including base plates connected to the front and to the bottom members, and each having a swinging catch and loops carried by the top at its front and 30 engageable with the fastening devices of the

front when the receptacle is in open position and engageable with the swinging catches of the bottom when the receptacle is collapsed.

4. A folding receptacle including inter-foldable front rear and end members and a movable top, means for movably connecting the top to the rear member, holding devices including base plates connected to the front and to the bottom members and each having 35 a swinging catch, and loops carried by the top at its front and engageable with the swinging catches of the front when the receptacle is in open position and engageable 40 with the swinging catches of the bottom 45 when the receptacle is collapsed.

5. A folding receptacle including inter-foldable front rear and end members and a movable top, means for movably connecting the top to the rear member, catch devices 50 mounted to swing relative to said bottom and front, and loops carried by said top and adapted to be engaged with the catch devices of the top when the receptacle is in open position and adapted to be engaged 55 with the catch devices of the bottom when the receptacle is collapsed.

In testimony whereof, I affix my signature.

JAMES SCARR. [L. s.]
